UNITED STATES PATENT OFFICE.

GEORGE M. HATHAWAY, OF NEW YORK, N. Y., ASSIGNOR OF ONE-HALF TO
CHARLES C. KEELER, OF SAME PLACE.

CAR STARTER AND BRAKE.

SPECIFICATION forming part of Letters Patent No. 291,594, dated January 8, 1884.

Application filed June 7, 1883. (No model.)

To all whom it may concern:

Be it known that I, GEORGE M. HATHAWAY, a citizen of the United States, residing at New York, in the county of New York and State 5 of New York, have invented certain new and useful Improvements in Car Starters and Brakes, of which the following is a specification, reference being had therein to the accompanying drawings.

10 This invention relates to certain improvements in car starters and brakes of that class in which the lost motion due to the checking of the car is stored up and utilized to give the initial movement to the car when again put in motion, in order to assist or relieve the horses 15 in overcoming the inertia at starting, as more fully hereinafter specified; and it has for its object to provide certain improved means whereby these purposes may be effected, as 20 more fully hereinafter specified.

The above-mentioned objects I attain by means illustrated in the accompanying drawings, in which—

Figure 1 represents a view of the bottom of 25 a car, showing my invention applied thereto; Fig. 2, a longitudinal vertical section of the same, showing my invention; Fig. 3, a view partly in longitudinal section, showing the axle, to which my invention is applied, detached; Fig. 4, a detached side elevation of a portion of my starting mechanism; Fig. 5, a 30 detached view of friction-wheel employed in connection with my starting mechanism; Fig. 6, a detached perspective view of a ratcheted sleeve employed in connection with my starting mechanism; and Fig. 7, a perspective view, 35 showing the clutch and releasing devices employed in connection with the starting mechanism.

40 The letter A indicates the truck or bottom of a car of ordinary or any approved construction; B, the forward axle, which is of the usual construction and journaled in the ordinary boxes, and C the common flanged wheels.

45 The letter D indicates the rear axle, which is enlarged for a portion of its length between the two ends, as indicated by the letter E. The said axle is journaled in the usual manner in boxes at each end, and has mounted 50 wheels of the ordinary construction. The said enlarged portion of the axle is provided

with right and left handed screw-grooves F and a collar, G, at one end, against which abuts one end of a spiral spring, H, which surrounds the enlarged portion of the shaft, the other 55 end abutting against the end of a hollow boss on the lever H', through which the enlarged portion of the shaft passes. The ends of the spring, respectively, are secured to the collar and the boss, as shown. Within the boss is 60 located loosely a sleeve, I, through which the enlarged portion of the shaft passes, the sleeve being ratcheted at one end, and adapted to engage suitable ratchets on the inside of the boss when the shaft travels in one direction, and 65 slip them when traveling in the opposite direction, for the purpose hereinafter specified. The said sleeve is provided with oblique ribs K internally, which are adapted to travel in one of the screw-grooves in the enlarged portion of 70 the shaft, and move it in the proper direction to compress the spring when the car is stopped, and thus store up the lost power.

The letter L indicates a beveled-edge friction-wheel, which is mounted loosely upon the 75 enlarged portion of the axle, and the hub of which sets against the plain edge of the sleeve I, mentioned, so as to hold it in place. This wheel is embraced by two bent levers, M N, having beveled grooves corresponding to the 80 bevel of the friction-wheel, the said levers being pivoted at one end to one end of the lever H', before mentioned, the other end of said levers M N being connected to the cross-piece P of a pin, R, passing through the opposite 85 end of the said before-mentioned lever H', by means of links R', the said pin being provided with a crank, S, to which the rear end of a rod, T, is secured, the forward end of said rod being secured to the lower end of a lever, 90 U, extending upward through a slot in the front platform, so as to be under the control of the driver. The lever H' is provided with a projection or lug, V, having an anti-friction roller, W, which travels between transverse 95 ways X and holds the levers in position as the parts are moved longitudinally upon the rear axle.

The operation of my invention will be understood in connection with the above description, and is as follows: While the car is 100 in motion the rear shaft travels independent

of the starting devices; but when the car is to be stopped the driver draws the lever U back, tightening the clamping-levers upon the friction-wheel. This holds said wheel from 5 rotation, and causes the same to travel along the shaft by reason of its inclined lugs traveling in one of the screw-grooves in the enlarged portion of the shaft before mentioned. This causes the boss on the lever H' to compress the 10 spring to an extent varying with the speed and momentum of the car, and operates as a brake to stop the same.

This device, it is evident, may also be applied as a brake in a similar manner when it 15 is desired to slacken the speed of the car on downgrades, or for other purposes.

When the car is to be started, the lever U is released, releasing the clamping-levers and the friction-wheel, permitting the same to 20 travel with the shaft. The ratcheted wheel, which previously slipped, is then engaged by the ratchets in the boss, holding it against rotation, causing the inclined lugs in said boss to travel in the other screw-grooves in the 25 shaft, so as to rotate the same in proper direction to start the car.

Having thus described my invention, what I claim is—

1. In a car-starter, the combination, with 30 the axle having enlarged portion and right and left hand screw-grooves, of the lever pro-

vided with the ratcheted boss containing a ratcheted sleeve having oblique internal lugs traveling in one of the grooves, a friction-wheel having oppositely-oblique lugs traveling in the other groove, the spiral mounted on the shaft, and mechanism for clamping the friction-wheel, substantially as and for the purposes specified. 35

2. The combination, with the enlarged right and left hand grooved axle, of the spiral spring, the lever provided with an internally-ratcheted boss, the ratcheted sleeve provided with internal oblique lugs, the friction-wheel provided with internal oblique lugs, the clamping-levers and their connecting-links the crank-pin, and the rod and operating-lever, all arranged substantially as and for the purposes specified. 40 45

3. The combination, with the right and left hand threaded shaft, of the sliding lever having a projection provided with an anti-friction wheel, the transverse ways between which said wheel moves, and the mechanism for clamping and moving the lever, substantially 50 55 as specified.

In testimony whereof I affix my signature in presence of two witnesses.

GEORGE M. HATHAWAY.

Witnesses:

EDMOND RICHARD,
F. M. MAYHEW.
